(57) **CLAIM**

The ornamental design for a training board, as shown and described.

DESCRIPTION

FIG. 1 is a perspective view of the training board in condition of use;

FIG. 2 is a top view of the training board;

FIG. 3 is a left side elevational view of the training board; with the right side being identical;

FIG. 4 is a front side elevational view of the training board; with the rear side being identical; and,

FIG. 5 is a bottom view of the training board.

The broken lines in the drawings depict environmental structure of the training board and form no part of the claimed design.

1 Claim, 4 Drawing Sheets

FIG. 5
